CLAIM

The ornamental design for a strap connector, as shown and described.

DESCRIPTION

FIG. 1 is a first perspective view of a strap connector showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a front perspective view shown with environmental structure; and,

FIG. 10 is an enlarged view of portion 10 shown in FIG. 9. The portions of the strap connector shown in broken line form no part of the claimed design. The broken line showing of straps and another strap connector in FIGS. 9 and 10 are for the purpose of illustrating environmental subject matter and form no part of the claimed design. The long dash-short dash broken lines indicate cutoff boundaries for enlarged detail portion views and form no part of the claimed design.
